UNITED STATES PATENT OFFICE.

GILBERT JOSEPH HART, OF NEW HAVEN, CONNECTICUT.

RAT-GUARD.

1,376,202.

Specification of Letters Patent. Patented Apr. 26, 1921.

Application filed November 11, 1920. Serial No. 423,450.

To all whom it may concern:

Be it known that I, GILBERT J. HART, a citizen of the United States, and a resident of New Haven, in the county of New Haven 5 and State of Connecticut, have invented a new and Improved Rat-Guard, of which the following is a full, clear, and exact description.

This invention relates to improvements in 10 rat guards, particularly to that form of device commonly employed to prevent rats from crawling aboard vessels via the mooring lines, an object of the invention being to provide an improved rat guard which may 15 be readily positioned upon a ship's hawser and readily removed therefrom.

A further object is to provide a device of 20 the character stated which will be simple and practical in construction, strong and durable in use, comparatively inexpensive to manufacture, and one which will automatically maintain its upright position on the hawser.

With these and other objects in view the 25 invention consists in certain novel features of construction, and combinations and arrangements of parts as will be more fully hereinafter described and pointed out in the claims.

30 In the accompanying drawings—

Figure 1 is a view in front elevation of my improved rat guard.

Fig. 2 is a view in side elevation thereof.

1 represents a metal plate which is provided with a finger receiving opening 2 at 35 its upper end to permit the ready handling thereof. The plate is slightly elongated and preferably formed with curved ends. The lower end of the plate is weighted by riveting or otherwise fastening a heavy piece of metal 3 thereto. The weight 3 is shaped in conformity with the lower end of the plate.

The plate 1 is formed with a curved rope receiving slot or recess 4 which extends 45 from the lower portion of one side of the plate inwardly and upwardly and its inner end is curved to conform to the shape of a hawser 5.

A longitudinal strengthening or reinforcing strip 6 is riveted to the face of the plate

which receives the weight 3. On the other face of the plate a keeper 7 is pivotally mounted adjacent one of its corners on a pin 8. This keeper 7 swings across the face of the plate 1 covering the slot 4 and is provided with a curved recess 9 coacting with the curved inner end of the slot to encircle the hawser 5.

The keeper is also provided with a weighted arm 10 which maintains the keeper in 60 the position illustrated engaging the hawser. A stop 11 in the form of an angle bracket is fixed to the face of the plate above the keeper and serves to limit the movement of the same when the rat guard is removed 65 from the hawser. A pin depending from the stop engages the hawser and prevents longitudinal movement of the plate on the hawser.

In placing the rat guard on a hawser the 70 keeper 7 is swung to one side and the plate is passed downwardly with the recess 4 receiving the hawser. As soon as the curved inner end of the recess 4 engages the hawser, the keeper 7 is released and the weight of 75 the arm 10 swings the keeper into the locking position illustrated.

The weight 3 will at all times retain the rat guard in upright position on the hawser, thus effectively preventing rodents from 80 crawling up the lines and on board a ship which is tied to the dock.

Various slight changes might be made in the general form and arrangement of the parts described without departing from the 85 invention, and hence I do not limit myself to the precise details set forth, but consider myself at liberty to make such changes and alterations as fairly fall within the spirit and scope of the appended claims.

90 I claim:

1. A device of the character stated, comprising a plate, a weight secured to one face of the plate adjacent its lower edge, a keeper pivoted to the other face of the plate, said plate having a rope receiving recess therein, and a weighted arm on the keeper maintaining the keeper in position to coat with the walls of said recess in encircling the rope.

2. A device of the character stated, com- 100

prising a plate, a weight secured to one face of the plate adjacent its lower edge, a keeper pivoted to the other face of the plate, said plate having a rope receiving recess therein, 5 and a weighted arm on the keeper maintaining the keeper in position to coact with the walls of said recess in encircling the rope,

an angle bracket fixed to the plate above the lower end of the rope receiving recess, a pin depending from the angle bracket and engageable with the rope to prevent movement of the plate longitudinally of the rope. 10

GILBERT JOSEPH HART.
